(57) **CLAIM**

The ornamental design for a bassinet, as shown and described.

DESCRIPTION

FIG. 1 is a perspective view of a bassinet showing my new design;

FIG. 2 is a front elevation view thereof, the rear being a mirror image;

FIG. 3 is a left side elevation view thereof, the right side being a mirror image;

FIG. 4 is a top plan view thereof;

FIG. 5 is a bottom plan view thereof;

FIG. 6 is a view of a front panel of the bassinet, shown separately for clarity of disclosure, with the opposite side of the front panel being a mirror image thereof;

FIG. 7 is a view of a rear panel of the bassinet, shown separately for clarity of disclosure, with the opposite side of the rear panel being a mirror image thereof;

FIG. 8 is a view of a left side panel of the bassinet, shown separately for clarity of disclosure, with the opposite side of the left side panel being a mirror image thereof;

FIG. 9 is a view of a right side panel of the bassinet, shown separately for clarity of disclosure, with the opposite side of the right side panel being a mirror image thereof;

FIG. 10 is a view of a cross length panel of the bassinet, shown separately for clarity of disclosure, with the opposite side of the cross length panel being a mirror image thereof;

(Continued)

FIG. 11 is a view of a first cross width panel of the bassinet, shown separately for clarity of disclosure, with the opposite side of the first cross width panel being a mirror image thereof;

FIG. 12 is a view of a second cross width panel of the bassinet, shown separately for clarity of disclosure, with the opposite side of the second cross width panel being a mirror image thereof; and,

FIG. 13 is a view of a bottom panel of the bassinet, shown separately for clarity of disclosure, with the opposite side of the bottom panel being a mirror image thereof.

The dashed lines are included for the purpose of illustrating portions of the bassinet that form no part of the claimed design.
